UNITED STATES PATENT OFFICE.

WILLIAM T. STRASSER, OF NEW YORK, N. Y.

SHOE-FASTENING.

SPECIFICATION forming part of Letters Patent No. 240,283, dated April 19, 1881.

Application filed February 18, 1881. (No model.)

To all whom it may concern:

Be it known that I, WILLIAM T. STRASSER, of the city of New York, in the county of New York, and State of New York, have invented 5 certain new and useful Improvements in Shoe-Fastenings; and I do hereby declare that the following is a full, clear, and exact description of the invention, that will enable others skilled in the art to which it appertains to make and 10 use the same, reference being had to the accompanying drawings, and to the letters of reference marked thereon, which form a part of this specification.

This invention relates to a means for securing 15 the shoe in place on the foot, in lieu of buttons, hooks, lacings, elastic webbing, or other devices, such as are usually employed in connection with shoes and gaiters.

The invention consists in a novel construction and combination, with a shoe or gaiter, of 20 a ribbed or flanged welt or strip, a series of rings or loops, a sliding or folding tongue or flap, and one or more hooks, buttons, or other projections, whereby provision is made for 25 closing and fastening the ankle portion of the shoe and as readily unfastening and opening the same in order to remove it, as hereinafter more particularly described.

In the accompanying drawings, Figure 1 30 represents a side view of a shoe provided with the improvement and in a position for inserting the foot therein. Fig. 2 is a similar view, showing the position of the parts when the shoe is closed. Fig. 3 is a transverse horizontal section taken in the line $\alpha\alpha$ of Fig. 2.

This invention may be applied to shoes or 35 gaiters of various descriptions, and may be arranged either in front or at one side, as may be preferred. By way of illustration it is here 40 shown as applied to the side of the shoe.

A represents a shoe with the upper divided at the side in a similar manner to that observed in the shoe commonly known as the "Congress gaiter." To the edges of the divided portion of said upper is attached a welt or strip, C, which may be of leather, metal, or other suitable material, and may be secured to the upper in any suitable manner. As here

shown it is attached to the V-shaped opening in the upper by being stitched to the edges thereof. This welt or strip is T-shaped in its cross-section—that is to say, it has a central longitudinal rib or bead, c, on one of its sides, and two flanges, d, projecting at right angles laterally from said rib or bead. The welt or strip is 50 secured to the edge of the opening with the rib or bead c nearest to the surface of the upper.

D represents a tongue or flap, of leather or other suitable flexible material, having its lower end secured to the upper below the commencement of the division thereof. To the inner surface of this tongue or flap are secured, by stitching or otherwise, a number of loops or divided rings, E, which slide on the flanges d of the welt or strip C, and which 55 may be made in one piece, if necessary. To the upper edges of the divided portions of the shoe are attached hooks G, or other suitable projections, for engagement with rings or eyelets f near the upper end of the tongue or 60 flap D.

When the shoe is to be put on the foot the parts are in the position shown in Fig. 1, with the ankle portion opened and the tongue or flap "gathered" at the lower part of the division in the upper. When the shoe is on the foot it is fastened by pulling up the tongue or flap D, so as to cause the rings or loops E to 65 slide on the welts C and draw the edges of the divided portions together, and then hooking the rings or eyelets f over the hooks or projections G, as shown in Fig. 2. To remove the shoe, the tongue or flap D is unhooked and then gathered to the first position, which allows the ankle portion of the shoe to open 70 sufficiently far to permit the foot to be withdrawn.

What I claim as new, and desire to secure by Letters Patent, is—

1. A boot or shoe provided with a T-shaped 75 strip or welt of leather, C, on each edge of the opening, and a suitable closing device, D, adapted to open and close the shoe-opening, substantially as shown and described.

2. A tongue or flap, D, provided with loops 80 or divided rings E, in combination with a

flanged welt or strip, C, attached to the divided ankle portion of a shoe, substantially as and for the purpose herein described.

3. A sliding tongue or flap, D, provided with rings or eyelets f, in combination with hooks or projections G on the divided ankle portion of a shoe, substantially as and for the purpose herein described.

In testimony that I claim the foregoing I have hereunto set my hand this 17th day of February, 1881.

WILLIAM T. STRASSER.
